FRANK W. BROOKE AND WILLIAM H. COSGROVE, OF PITTSBURGH, PENNSYLVANIA, ASSIGNEES TO SWINDELL-DRESSLER CORPORATION, OF PITTSBURGH, PENNSYLVANIA, A CORPORATION OF PENNSYLVANIA

CONVEYING APPARATUS

Application filed June 17, 1930. Serial No. 461,832.

This invention relates generally to conveying apparatus, and more particularly to apparatus adapted to convey sheets through a heat treating furnace.

Sheets are ordinarily conveyed through heat treating furnaces on discs carried by rolls, the discs and rolls ordinarily being made of some high melting point alloy, such as an alloy of nickel and chromium. So far as we are aware, it has been the practice up to the present time to cast the roll in one piece. Since the rolls are large, a good deal of difficulty is encountered in the casting process. The difficulties of casting these rolls are great, not only because of the size of the rolls, but also because the high melting point alloys have a tendency not to knit together properly when two streams of the alloy are run together. It is desirable to make these rolls as light as possible and still have sufficient strength to support the conveying discs and the material which is conveyed through the heat treating furnace. Accordingly, it is very difficult to cast a large roll from a high melting point alloy, particularly if it is desired to produce a roll having a thin wall.

According to the present invention, we decrease the difficulties incident to the casting operation by splitting the roll transversely into a plurality of parts. This eliminates or decreases the difficulties of properly positioning and venting the cores and also results in a roll having more uniform roll thickness. The molten metal has a shorter distance to run so that it is not cooled below the point at which molten streams of metal will properly knit together. The smaller sections of the roll made in accordance with our invention enables one to cast them in a vertical position.

In the accompanying drawings, which illustrate two preferred embodiments of our invention,

Figure 1 is a plan view of a roll split into two sections, parts being broken away and other parts being shown in section.

Figure 2 is a similar view illustrating a roll split into more than two parts;

Figure 3 is a transverse section on the line III-III of Figure 1, and

Figure 4 is a transverse section on the line IV-IV of Figure 2.

Referring more particularly to Figure 1, the roll indicated generally by the numeral 2 is divided into two parts 3 and 4, the split being made at the center line of the roll. The part 4 is provided with a projection 5 which fits into a recess 6 in the roll part 3 in order to provide a good seat and properly align the parts. Each of the roll parts 3 and 4 is provided at adjacent ends with an outwardly radially extending flange 7 which terminates in a horizontally extending flange 8. The flanges 7 are secured together by bolts 9, thereby uniting the two roll parts 3 and 4.

Each of the roll parts 3 and 4 is provided with a plurality of material conveying discs 10 spaced longitudinally of the roll. These discs may be of any usual or desired construction and may be secured to the roll in any desired manner. However, it is preferred to use discs of the type described in our copending application, Serial No. 429,042, filed February 17, 1930. The discs described in our copending application can be made much lighter than those ordinarily employed. Accordingly, when such discs are used, the roll itself may be made lighter by reducing the wall thickness. The decrease in wall thickness would ordinarily result in casting difficulties, but these difficulties may be overcome by dividing the roll into a plurality of parts, as described in the present application.

The flanges 7 extend outwardly from the roll for a distance substantially equal to the distance between the supporting surfaces of the discs 10 and the roll. This provides an arrangement in which the flanges not only provide means for securing the roll parts together, but in which the peripheries of the flanges act as material supporting and conveying means.

The embodiment shown in Figure 2 is generally similar to that hereinabove described, but the roll is divided into more than two parts. The portion of the roll which is shown is divided into three parts 21, 22 and 23, and since Figure 2 illustrates substantially one-half of the entire roll, the roll, according to

this embodiment, would be divided into six parts.

The invention, however, contemplates dividing the roll into as many parts as may be found necessary or desirable. The roll parts 21, 22 and 23 are provided with outwardly radially extending flanges 7a similar to flanges 7 in Figure 1. The flanges 7a terminate in horizontal flanges 8a, the flanges 7a being united by bolts 9a. Projection and recess engagement constituting the projections 5a and the recesses 6a also is provided for fitting the roll parts together.

Intermediate the flanges 7a on the roll parts 22 and 23 are secured material conveying discs 25. These discs are made in two parts 26 and 27 secured together by bolts 28. Each part has a hub 29 which bears against the roll, a web 30, and a rim 31 which supports the material being conveyed through the furnace. The web 30 is provided with openings 32 to reduce the weight of the disc.

In each of the embodiments, the adjacent ends of the roll parts are provided with outwardly extending flanges which not only provide means for securing the roll parts together, but also themselves act as material supporting and conveying means. The invention is particularly applicable to the production of rolls cast from an alloy having a high melting point, but it may be used irrespective of the material of which the rolls are made.

We have illustrated and described two preferred embodiments of our invention. It is to be understood, however, that the invention may be otherwise embodied within the scope of the following claims.

We claim:

1. Apparatus for conveying material through a furnace comprising a cast metal roll split transversely into a plurality of parts, material supporting discs spaced longitudinally of the roll, the roll having outwardly radially extending flanges thereon at the split, and means for connecting the flanges of adjacent roll parts.

2. Apparatus for conveying material through a furnace comprising a cast metal roll split transversely into a plurality of parts, material supporting discs spaced longitudinally of the roll, the roll having outwardly radially extending flanges thereon at the split, and means for connecting the flanges of adjacent roll parts, the flanges and discs acting as material supporting and conveying means.

3. Apparatus for conveying material through a furnace comprising a cast metal roll split transversely into a plurality of parts and having outwardly radially extending flanges adjacent the split, and means for connecting the flanges of adjacent roll parts, the flanges being adapted to act

as supporting and conveying means for the material.

4. Apparatus for conveying material through a furnace comprising a cast metal roll split transversely into a plurality of parts and having outwardly radially extending flanges adjacent the split, means for connecting the flanges of adjacent roll parts, adjacent roll parts having projection and recess engagement, material supporting discs spaced longitudinally of the roll, the outer surfaces of the discs and flanges extending substantially equal distances from the roll so that the discs and flanges are adapted to support the material.

5. Material conveying apparatus for heat treating furnaces, comprising a cast roll of high melting point alloy, the roll being split into a plurality of parts and having outwardly radially extending cast flanges adjacent the split, means for connecting the flanges of the adjacent roll parts, adjacent roll parts having projection and recess engagement, material supporting discs of high melting point alloy spaced longitudinally of the roll, the outer surfaces of the discs and flanges extending substantially equal distances from the roll so that the discs and flanges are adapted to support the material.

6. Apparatus for conveying material through a furnace comprising a roll split transversely into a plurality of parts, material supporting discs spaced longitudinally of the roll, the roll having outwardly radially extending flanges thereon at the split, the outer surface of the discs and flanges extending substantially equal distances from the roll so that the discs and flanges are adapted to support the material, and means for connecting the flanges of adjacent roll parts.

In testimony whereof we have hereunto set our hands.

FRANK W. BROOKE.
